CLAIM

The ornamental design for a centrifugal fruit and vege-
table juice extractor, as shown.

DESCRIPTION

FIG. 1 is a perspective view of a centrifugal fruit and
vegetable juice extractor showing my new design;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof; and
FIG. 7 is a bottom plan view thereof.
